UNITED STATES PATENT OFFICE.

DAVID R. COLLIER, OF GARDNER, MASSACHUSETTS, ASSIGNOR TO COLLIER-KEYWORTH COMPANY, OF GARDNER, MASSACHUSETTS, A CORPORATION OF MASSACHUSETTS.

CHAIR-IRON.

1,336,510.

Specification of Letters Patent. Patented Apr. 13, 1920.

Application filed December 19, 1918. Serial No. 267,458.

To all whom it may concern:

Be it known that I, DAVID R. COLLIER, a citizen of the United States, residing at Gardner, in the county of Worcester and State of Massachusetts, have invented new and useful Improvements in Chair-Irons, of which the following is a specification.

This invention has for its object to provide a chair iron which is simple and inexpensive in construction and which will permit the back to yield relatively to the seat. One of the features of advantage incident to the construction of the iron is that most of the parts may be stamped out of sheet metal and bent or drawn into shape, thereby enabling the production of a light and durable iron.

On the accompanying drawings—

Figure 1 represents in side elevation a chair embodying the invention.

Fig. 2 represents a plan view of the iron.

Fig. 3 represents a section on the line 3—3 of Fig. 2 and shows the parts in their normal positions.

Fig. 4 represents a similar section with the back of the chair at the end of its rearward movement.

Fig. 5 represents a section on the line 5—5 of Fig. 2 and shows in section a portion of the seat.

Fig. 6 represents a section on the line 6—6 of Fig. 3 and shows the means for permitting adjustment of the back standard.

Fig. 7 shows the rear end of the forked rocker.

Fig. 8 represents a section on the line 8—8 of Fig. 1 and illustrates the means by which adjustment of the back in relation to the standard is permitted.

Fig. 9 represents a section on the line 9—9 of Fig. 8.

Fig. 10 illustrates the plate which is affixed to the back.

Referring to Fig. 1, it will be observed that the chair as illustrated is provided with a pedestal, in the hub of which is supported the spindle 20. Preferably, though not necessarily, the hub and the spindle 20 are constructed as illustrated and described in my application Serial No. 232,020, filed May 2, 1918. In accordance with the construction described in said application, the spindle may be adjusted vertically in reference to the pedestal, and after adjustment it may

rotate freely without causing any vertical movement of the spindle.

Affixed to the upper end of the spindle, there is an open head indicated as a whole in Fig. 1 at 21. This head is formed of a flat metal strip bent in to the form of a yoke with the horizontal transverse bar 22 and with upstanding sides 23. Between the sides 23, 23, there is a transverse sheet metal reinforcement or bridge 25 the ends of which are down-turned, as shown in Fig. 5, and secured by rivets 26 to the sides 23 of the head. The spindle 20 has a bead 27 which engages the transverse bar 22, through an aperture in which the spindle is passed; and the upper extremity of the spindle is inserted in an aperture in the cross-bar 25 and its end is upset therein as shown in Fig. 5. The head is thus rigidly secured to and supported upon the upper end of the spindle so as to rotate therewith. The head supports the spider, which in the present instance consists of the two bars 28, 28, which are formed of sheet metal and bent into proper shape. Each bar is formed with a horizontal web 29 and a vertical web 30. The horizontal webs 29 extend toward each other and they rest upon the upper extremities of the sides of the head. The vertical webs 30 are secured to the sides 28 by rivets 31, 31. The chair seat 32 rests upon the spider and is secured thereto by wood screws indicated at 33. By reason of this construction, the seat, the spider, the head and the spindle are all secured rigidly together. The back of the chair, which is indicated at 34, may be of any suitable shape in accordance with the uses to which the chair is to be put. As illustrated, it consists of a curved wooden member which is adjustably supported by a standard 35. Of course these parts need not be made out of wood, although that is the material of which these parts are ordinarily made. The back standard 35 near its upper end is provided with a longitudinal vertical slot 36, and to the rear face of the back 34 there is secured a plate 37 formed with loop members 38 which project into the slot 36, thereby to preclude any rocking movement of the back relatively to the standard. These loops 38 constitute guide members for co-operation with the slot. The plate is shown in Fig. 10 and it is provided with apertures

conveniently located, through which screws 39 may be passed into the back 34. The plate is provided with a rearwardly offset portion 40 having a square aperture 41 through which a bolt 42 extends rearwardly. The bolt is inserted through the plate before the latter is attached to the back, so that, when the latter is in place, the head of the bolt occupies the recess formed by the offset portion 40. Adjacent the head the bolt is angular so as to fit the aperture 41. On the end of the bolt which is passed through the slot 36, there is a washer 43 and a nut 44. This nut consists of a sheet-metal stamping which is so drawn as to afford a hub-like portion 45 of sufficient length for the formation of threads to engage the threaded portion of the bolt. The standard 35 is supported upon a rocker so as to be angularly adjustable in reference thereto. Instead of supporting the rocker upon a special base attached to the seat or to a base plate, it is pivotally supported upon the head, and therefore supported by the spindle 20. The rocker in plan view is forked. It consists of the two members 46, 46, which at their rear ends are brought into facial contact and are firmly united by rivets 47, 47. The forward portions of the members 46 are spaced apart and are parallel so as to fit between the sides 23 of the head. A pintle 48 serves as the pivot or fulcrum for the rocker and it is passed through apertures in the members 46 and in the sides of the head, the ends of the pintle being upset to form heads 49 to prevent dislocation thereof. It will be noted that the axis of the pintle 48 preferably intersects the axis of the spindle and is perpendicular thereto. The rear end of the rocker, as shown in side elevation, has a lateral or upward extension in which there is formed an open slot or notch 50. The lower end of the standard is slit or bifurcated so as to fit over the end of the rocker and it has a pintle 51 which occupies the lower end of the slot 50. Below the slot 50 there is an arcuate slot 52 whose center is coincident with the pintle 51, and a bolt 53 passed through the lower extremity of the standard occupies the slot 52. The headed end of the bolt is square or angular, so that, when forced into one of the arms of the standard, it will not rotate. Upon the threaded end of the bolt there is placed a loose washer 54 and a nut 55 which is similar to the nut 44 previously described. By tightening the nut, the lower end of the standard may be tightly clamped against movement. The means for affording adjustment of the standard in reference to the rocker is in general not an unusual construction. The spring mechanism for the rocker is so arranged as to exert a yielding pressure against the rocker to hold its rear

end normally in elevated position as shown in Fig. 3, but to permit it to be depressed against the pressure of the spring to the position shown in Fig. 4, the latter illustrating the lower limit of the movement of the rocker. To the head there is secured an upwardly projecting plate or abutment 56, the lower end of which is provided with lugs 57 which pass through holes in the bottom plate of the head and which are upset as shown so as to hold the plate 56 in place. This plate also is braced by its engagement with one of the side edges of the cross brace or plate 25 and it is located between the two members of the rocker which straddle it. The upper portion of the plate 56 has an aperture through which a bolt 58 loosely passes, the head 59 of the bolt engaging the rear face of said plate 56. Upon the end of the bolt, there is a tubular sleeve nut 60 having a cross-pin 61 to facilitate its rotation. A compression spring 62 encircles the bolt and its front end bears against a flanged sheet-metal circular spring plate 63 which in turn bears against the end of the nut 60. The other end of the spring engages a similar dished plate 64, and this latter plate is pressed by the spring against a trunnioned cross-bar 65, the trunnions of which are journaled in apertures formed in the members 46 of the rocker. The rearward pressure of the spring, which is exerted against the trunnioned plate 65, forces the rear end of the rocker upwardly until the upper edges of the members 46 thereof, which are in the rear of the pintle 48, engage and rest against the under sides of the horizontal webs of the spider. The front ends of the members 46 of the rocker project forwardly far enough in front of the pintle 48 to act as stops and limit the downward movement of the rear end of the rocker by their engagement with the horizontal webs of the spider.

The construction which I have thus illustrated and described provides for the location of the spring mechanism in the central portion of the chair iron and directly over the spindle. Of course while I have shown but one spring, it is apparent that at least two springs could be utilized if desired without departing from the spirit and scope of the invention as expressed in the claims. Various changes may be made in the details of the construction and arrangement of the parts as illustrated and described without departing from the spirit and scope of the invention defined in the claims.

Having thus explained the nature of my said invention and described a way of making and using the same, although without attempting to set forth all of the forms in which it may be made or all of the modes of its use, what I claim is:

1. A chair iron comprising a yoke, a

- 5 pinte supported by the sides of said yoke, a back-supporting rocker extending into the yoke and pivoted on the pinte, an abutment on the head, a member on the rocker, a bolt engaged with the abutment and passing through said member, a nut on the bolt, and a spring interposed between the nut and the said member on the rocker.
- 10 2. A chair iron comprising a spindle, a head thereon to which a chair seat may be affixed, a back-supporting rocker, and a pivot therefor supported by the head above and approximately intersecting the axis of the spindle.
- 15 3. A chair iron comprising a spider to which the seat may be affixed, a spindle, a head consisting of an inverted yoke having its cross bar fixed upon the end of the spindle and having its sides secured fixedly to the spider, and a spring-pressed back-supporting rocker extending into the yoke and pivoted to the sides thereof.
- 20 4. A chair iron comprising a spider to which the seat may be affixed, a spindle, an open head on the end of the spindle, fixedly secured to the spider and having parallel members, a back-supporting rocker extending into the head between said members thereof, and a helical compression spring interposed between the rocker and the head.
- 25 5. A chair iron comprising a spider to which the seat may be affixed, a spindle, an open head on the end of the spindle, and having the spider affixed thereto, a forked back-supporting rocker extending into the open head, an abutment on said head located between the members of the rocker, and spring mechanism engaging the rocker and the abutment.
- 30 6. A chair iron comprising an open head on which a seat may be fixedly secured, a pinte passing transversely through said head, a forked rocker having its members pivoted on said pinte and lying between the sides of said head, a cross bar engaged with the members of said rocker, an abutment secured to said head and located between the members of the rocker, and a spring interposed between said cross bar and said abutment.
- 35 7. A chair iron comprising an open head on which a seat may be fixedly secured, a pinte passing transversely through said head, a forked rocker having its members pivoted on said pinte and lying between the sides of said head, a cross bar having its ends trunnioned in the members of the forked rocker, an abutment secured to the head and located between the members of the rocker, a bolt passing through apertures in the rocker and the abutment, a nut on the bolt, and a compression spring interposed between the cross bar and the nut.
- 40 8. A chair iron comprising an open head on which a seat may be fixedly secured, a pinte passing transversely through said head, a forked rocker having its members pivoted on said pinte and lying between the sides of said head, a cross bar having its ends trunnioned in the members of the forked rocker, an abutment secured to the head and located between the members of the rocker, a bolt passing through apertures in the rocker and the abutment, a nut on the bolt, and a compression spring interposed between the cross bar and the nut.
- 45 9. A chair iron comprising an open head on which a seat may be fixedly secured, a pinte passing transversely through said head, a forked rocker having its members pivoted on said pinte and lying between the sides of said head, a cross bar having its ends trunnioned in the members of the forked rocker, an abutment secured to the head and located between the members of the rocker, a bolt passing through apertures in the rocker and the abutment, a nut on the bolt, and a compression spring interposed between the cross bar and the nut.
- 50 10. A chair iron comprising a spindle, a head on the upper end thereof having upright members, means by which a seat may be fixedly secured to the head, a rocker pivoted to the members on the head to move about an axis substantially intersecting the axis of the spindle, and a compression spring mechanism engaging the head and the rocker and located above and across the spindle.
- 55 11. A chair iron comprising a spindle, a head on the upper end thereof, means by which a seat may be fixedly secured to the head, a rocker pivoted to the head to move about an axis substantially intersecting the axis of the spindle, a bolt above and intersecting the axis of the spindle, an abutment on the head engaging the headed end of the bolt, a nut on the end of the bolt, a member on the rocker, and a spring interposed between said member and said nut.
- 60 12. A chair iron comprising a spindle, an inverted yoke-shaped head on the upper end thereof, an upstanding abutment on the head, a transverse pinte passed through the head, a forked back-supporting rocker pivoted on the pinte, a cross bar arranged in the fork of the rocker, a compression spring arranged to exert its pressure against the abutment and the cross bar, and means on the head for engaging the rocker to limit its movement in opposite directions about the pinte.
- 65 13. A chair iron comprising a spindle, an inverted yoke-shaped head on the upper end thereof, an upstanding abutment on the head, a transverse pinte passed through the head, a forked back-supporting rocker pivoted on the pinte, a cross bar arranged in the fork of the rocker, a compression spring arranged to exert its pressure against the abutment and the cross bar, and spider arms affixed to the head and having webs overlapping the rocker to limit the oscillatory movement of the rocker.

4

14. A chair iron comprising a spider, an open head riveted to the spider, a spindle secured to the head, an upstanding abutment plate affixed to the head, a transverse 5 pintle in the head, a forked rocker straddling the abutment plate and pivoted on the pintle, a cross bar trunnioned to the rocker and arranged in the fork thereof, a bolt passing through the abutment plate and the 10 cross bar, a nut on the end of the bolt, and a compression spring between the nut and the cross bar.

15. In a chair iron, a head having upstanding sides, a spider fixedly secured to 15 said sides, a forked rocker having rearwardly convergent arms, the forward ends of which are located between the upstanding sides of the head, a cross bar extending between the divergent ends of the rocker arms, 20 and a pintle pivotally connecting said rocker to the said upstanding sides of the head adjacent said cross bar.

16. A chair iron comprising an inverted yoke with upstanding sides, a pintle sup-

ported by said sides, a rearwardly extending 25 forked rocker whose arms are rearwardly convergent, a crossbar bridging said arms of the rocker, a vertical abutment on the yoke and a helical compression spring exerting pressure against said abutment and said 30 crossbar, in combination with a back standard bifurcated at its lower end and straddling the convergent ends of the rocker arms.

17. A chair iron comprising a spindle, an upstanding yoke thereon on which a seat 35 may be fixedly secured, a rearwardly-extending back-supporting rocker extending into the yoke and pivoted to the arms thereof, a stationary abutment on the yoke, a bolt engaged with the abutment and having an 40 adjustable nut thereon, a compression spring having one end engaging said nut, and means on the rocker engaging the other end of said spring.

In testimony whereof I have affixed my 45 signature.

DAVID R. COLLIER
